UNITED STATES PATENT OFFICE.

MARK SHOELD, OF CHICAGO, ILLINOIS, ASSIGNOR TO ARMOUR FERTILIZER WORKS, OF CHICAGO, ILLINOIS, A CORPORATION OF NEW JERSEY.

POLYPHASE ELECTRIC FURNACE.

1,317,328.

Specification of Letters Patent. Patented Sept. 30, 1919.

Application filed November 20, 1918. Serial No. 263,420.

To all whom it may concern:

Be it known that I, MARK SHOELD, a subject of the King of Sweden, residing at Chicago, in the county of Cook and State of Illinois, have invented certain new and useful Improvements in Polyphase Electric Furnaces, of which the following is a specification.

The prime object of the present invention is to provide an electric heating furnace for chemical reactions capable of advantageously using polyphase alternating electric currents with their well-known economical advantages in such way as to secure the proper distribution of current flow to effect substantially uniform and even heating of the material to be treated, which is usually conveniently supplied in the form of briquets. To this end the electrodes of the circuit are so arranged or grouped and spaced apart and so associated with or embedded in the material to be chemically treated that the resulting heating is practically uniform throughout the mass. In some forms of the invention, as in the case of three-phase circuits, the electrodes are so inserted or embedded in the body of material as to constitute a probable combination of delta or mesh arrangement with the well-known star connection. In other instances, different connections are suitable and effective. It is desirable, however, in order to avoid excessive unbalancing of the system, and for other reasons, to prevent the briquets of material from individually fusing or becoming welded together under the great heat attained, and to this end practically infusible, resistance, heat elements desirably of greater specific conductivity than the briquets themselves are mixed or interspersed with the latter, whereby by contacting more or less with one another they form current paths in parallel relation which shunt or divert the currents sufficiently to themselves and away from the briquets so that the resistors by reason of the currents flowing through them become highly heated and transmit their heat by conduction to the neighboring briquets, the latter becoming thus hot enough to effect the desired chemical reactions, but not hot enough to fuse. Obviously, if the briquets alone were used and any one or more melted or became fused together, the electrical resistance at this point would be greatly re-

duced, the current correspondingly increased, and the desired balance of the electrical system disarranged and upset with obvious objectionable uneven heating.

The invention is susceptible of a variety of embodiments, and, in order that its underlying principles may be understood by those skilled in the art, in the accompanying drawings, forming a part of this specification, and to which reference should be had in connection with the following detailed description, I have shown several convenient concrete examples of the invention employed in advantageous manner, each illustrating a horizontal cross-section through the corresponding furnace structure, the refractory or heat-resisting elements and other parts being omitted.

In this drawing,

Figure 1 is a horizontal cross-section showing one style of three-phase electrode arrangement;

Fig. 2 illustrates in similar manner a modified three-phase construction;

Fig. 3 shows a two-phase arrangement with a common return; and

Fig. 4 also indicates a two-phase system of modified type.

Since the two and three-phase systems are the most common polyphase systems in use and hence most readily available, the forms of furnace devices incorporating this invention have been illustrated as of those styles or character, but it is to be understood that the invention is not necessarily limited to these particular types of furnaces or electric systems.

Referring first to the structure shown in Fig. 1 it will be noted that the furnace comprises an outer hollow graphite or similar electrode 10 of general elongated or elliptical form in cross-section incasing or inclosing a pair of spaced, graphite electrodes 11 and 12, the three being connected to the like number of terminals of a three-phase circuit of suitable voltage. The comparatively-uniform mixture of briquets 13 and resistor-elements 14 is continuously slowly fed down through the spaces around and between these electrodes in a steady stream, the resistance-members collectively or jointly forming a number of paths in parallel for the current to pass from electrode to electrode. The specific resistance of the resistor-elements or that occasioned by their comparatively poor

electrical contact with one another generates or causes sufficient heat to raise the temperature of the adjoining briquets to bring about the desired chemical effect, it being understood that in many instances gas of one kind or another is caused to traverse the mixture during such heating. As an illustration, the briquets, somewhat fusible under high temperature, may be composed of comminuted carbon, alumina, and a suitable binder and the resistance elements may be of carbon in one form or another which is comparatively non-fusible, and the gas may be nitrogen or one rich in nitrogen. It should be observed that these resistance-members act collectively or unitedly in groups or sets as heat-producing elements, and also as mechanical separators or spacers for the briquets. Desirably the electrodes 11 and 12 are separated such a distance from one another with respect to their distances from the larger outer electrode as to produce a substantially or practically uniform or even heating of the mixture occasioned by similar current distribution. This arrangement of electrodes approximates a delta connection between the three-phase terminals with probably some of the currents flowing in star connection distribution.

In Fig. 2 a somewhat different disposition of electrodes is shown. In this case three electrodes 20, 21 and 22 are placed in equilateral triangular arrangement, or, in other words, spaced equally apart, and connected to the terminals of a three-phase circuit. Around these and spaced therefrom is an outer, grounded, neutral or common return electrode 23 of general triangular form so as to be practically equally distant from all of the three electrodes within it. As in the previous instance the mechanical mixture of briquets and resister bodies passes slowly down between and around these various electrodes, filling the spaces as shown. Viewed from one standpoint electrode 23 is the common neutral or joint return electrode for the system, the currents flowing between the three inner electrodes and it in a manner well understood. The grounding of the neutral is of advantage if the system becomes somewhat electrically unbalanced thus completing the common return. Viewed somewhat differently, since the currents can flow directly from one inner electrode to another and from one inner electrode to the outer one and back to another inner one, the system may be considered as a delta connection. As a matter of fact, the arrangement is probably a combination of both styles of connection with the resulting advantages of the practically uniform distribution of currents and heat throughout the body of briquets. The inner electrodes are spaced from one another

and from the outer electrode, such distances as to result in this substantially even heating effect. Obviously, the ground connection may be omitted if desired.

In the system of Fig. 3 the two inner electrodes 30 and 31 are connected to two terminals 32 and 33 of a two phase circuit, the outer ring electrode 34 being in electrical connection with a common return wire 35, the spacing of the electrodes apart being such that the mass or mixture of briquets and resistance-elements is practically evenly heated.

Another two-phase circuit arrangement is presented in Fig. 4 wherein the furnace has an outer electrode 40 connected to the common return conductor 41 and containing two chambers or compartments each accommodating one of the two electrodes 42 and 43 connected to the two-phase terminals 44 and 45. Each of these heat compartments contains its own body of mixture all parts of which are heated in like degree. The currents in this instance flow directly between each electrode and the common outer electrode.

In these drawings no attempt has been made to show accurately the exact sizes and shapes of electrodes nor the precise disposition or spacing apart of the same, it being the purpose merely to set forth the general principles of the invention in such a way as to enable any one skilled in the art to practice the invention and reap the benefits of its employment. It will be clear, therefore, that the invention is not limited to the precise and exact structural features shown and that these may be modified within comparatively wide limits without departure from the essence and substance of the invention and without the sacrifice of any of its substantial benefits and advantages. Accordingly it is the aim of the appended claims to cover all modifications which are within the spirit and scope of the invention.

I claim:

1. A polyphase alternating-current electric heating furnace for chemical reactions, comprising a plurality of spaced electrodes adapted to be connected to the terminals of a polyphase electric circuit and to be in contact with the body of material to be heated, one of said electrodes comprising a surrounding tubular body through which the material is adapted to pass, the disposition and spacing apart of said electrodes producing substantially-uniform heating of the material, substantially as described.

2. The combination of a polyphase alternating-current electric heating furnace for chemical reactions and a body of material to be heated thereby comprising a mechanical mixture of briquets to be chemically modified and comparatively-in fusible resister-

elements, said furnace comprising a plurality of spaced electrodes connected to the terminals of a polyphase electric circuit and in contact with said body of material to be heated through which the currents pass, one of said electrodes comprising a surrounding tubular body through which such mixture is adapted to pass, the disposition and spacing apart of said electrodes producing substantially-uniform heating of the briquets, substantially as described.

3. A polyphase alternating-current electric heating furnace for chemical reactions, comprising a plurality of spaced electrodes adapted to be connected to the terminals of a polyphase electric circuit, one of said electrodes comprising a surrounding tubular body through which the material to be heated is adapted to pass, the remaining electrodes being adapted to be embedded in such material, the disposition and spacing apart of said electrodes producing substantially-uniform heating of such material, substantially as described.

25. 4. The combination of a polyphase alternating-current electric heating furnace for chemical reactions and a body of material to be heated thereby comprising a mechanical mixture of briquets to be chemically modified and comparatively-infusible resistor-elements, said furnace comprising a plurality of spaced electrodes connected to the terminals of a polyphase electric circuit, one of said electrodes comprising a surrounding tubular body through which the material to be heated is adapted to pass, the remaining electrodes being embedded in the body of material to be heated through which the currents pass, the disposition and spacing apart of said electrodes producing

substantially-uniform heating of the briquets, substantially as described.

5. A polyphase alternating-current electric heating furnace for chemical reactions, comprising an outer tubular electrode 45 through which the material to be heated is adapted to pass, said electrode being connected to the common return conductor of a polyphase circuit, and a plurality of electrodes within and spaced away from said outer electrode and connected to the remaining terminals of said circuit, the disposition of said electrodes being such that the material to be treated disposed around and between them will be substantially-uniformly 50 heated, substantially as described.

6. A polyphase alternating-current electric heating furnace for chemical reactions, comprising an outer electrode forming a plurality of chambers through which the material 60 to be treated is adapted to pass and each containing an electrode spaced away from the walls of its chamber and adapted to be embedded in the material traversing its chamber, substantially as described. 65

7. A polyphase alternating-current electric heating furnace for chemical reactions, comprising an outer electrode connected to the common return conductor of a polyphase circuit and shaped to provide a plurality of chambers through which the material to be treated is adapted to pass, and each containing an electrode spaced away 70 from the walls of its chamber and adapted to be embedded in the material traversing its chamber, said inner electrodes being connected to the remaining conductors of said polyphase circuit, substantially as described. 75

MARK SHOELD.
